TYPESETTING DEVICE

Jay Will Lysons, New York, N. Y.

Application January 15, 1937, Serial No. 120,659

7 Claims. (Cl. 276—37)

My invention relates to type setting devices in general and particularly to type assembling devices or tools extensively in use in connection with multigraphs and similar printing machines.

- 5 5 One object of my invention is to provide an improved type-setting or assembling device enabling an operator to quickly remove, insert or interchange any of the assembled types at any point of the line.
- 10 10 Another object is to provide certain improvements upon the type filling or setting device to facilitate the interchanging of individual type, or type slugs or spaces.

15 15 A further object is to provide ejecting means whereby types accidentally thrown or fallen off their support and lodged within the device can be quickly removed.

20 20 Still another object is to provide an improved supporting and locking means to facilitate the operating of the device.

These and other objects I attain by the combination of various parts and elements fully described in this specification and illustrated in the accompanying drawing in which:

25 25 Figure 1 represents a top view of the preferred form of embodiment of such a type setting device.

Figure 2 represents a side view of Figure 1 and also showing the supporting means for the device.

30 30 Figure 3 represents a sectional side view of Figure 2 along lines 3—3 in Figure 2.

Figure 4 represents a sectional view along lines 4—4, enlarged.

35 35 Figure 5 represents an enlarged sectional view along lines 5—5.

Figure 6 represents an enlarged view along lines 6—6, also indicating the position of an inserted type, or slug.

40 40 Figure 7 represents a side view of the preferred form of the type, most suitable for the purpose.

Figure 8 represents a top view of a portion of the setting device, indicating a type in the process of removal.

45 45 Similar characters refer to similar parts throughout the various views.

In multigraphs or similar printing machines it is common practice to set each individual line of print in type, by means of a type setting device 50 similar to the one shown in Figures 1 and 2. After the process of type assembly the thus completed line is inserted into suitable grooves provided in the printing drum of the machine.

55 55 The assembling or setting of a line in type, being an accurate and time taking procedure, is as a

rule performed by labor highly skilled in this work. Any misplacement or error in assembling the types always results in removing part, sometimes all of the types, from the device. To attain perfect printing, that is equal length of 5 every line of print, it invariably is necessary to insert, at various points, so-called blanks or spacers, of course necessitating again the removal and re-setting of the types. Obviously much time is lost, even by experienced operators, to 10 obtain perfect lines of print by this unavoidable removing and re-setting of types.

To overcome these disadvantages I propose to incorporate certain improvements and modifications eliminating the necessity of removing 15 lines of type, to insert blanks or spacers, or the sometimes imperative interchanging of types.

The typesetting tool or device practically universally in service comprises an elongated slotted tubular shell, very similar in appearance of the 20 one shown in Figure 1, except no means are provided to permit the insertion or removal of types, without first removing part or all of the types.

To attain my objects and also facilitate the operating of the device I co-ordinate the functions of the three principal members involved, first the type-setting device proper 1, second the type proper 3, and third the supporting bracket 2, indicated in Figures 1, 2, and 3.

The type-setting tool or device 1 comprises a 30 slotted tubular body provided with a longitudinal slot 1a, extending over the entire length of body 1. Slot 1a, serves to facilitate the insertion of the individual types 3, which in turn are provided with suitable notches 3a, engaging the edges 35 of the body, formed by slot 1a, as shown in Figures 6 and 7. In actual practice, up to the present, these individual types are manufactured and furnished only in full thickness, indicated in dotted lines in Figure 7, and can only be inserted 40 or discharged at the ends of body 1. Types of this character cannot be interchanged or removed without first disposing of all types positioned ahead of same.

Now by properly narrowing the lower portion 45 3b, of type 3, leaving a practically square neck part 3c, the operator is enabled to remove or insert any of the types at any point by a simple 90 degree turn of the type, as indicated in Figure 8. With this provision types or blanks can be 50 inserted or interchanged, at will, even with the ordinary type setting devices.

Due to lack of space it will not always be possible to remove types by this method and other means must be found to make this possible. In 55

Figures 4 and 6, I have illustrated certain means whereby standard types of any thickness may be easily removed or inserted, at any desired point inside of the body holders 1b. For this purpose 5 an elongated shield or door member 1c, suitably fastened to slotted grip spring members 1d, adopted to rotatably move within a corresponding depression in body 1, is provided. This rotatable shield 1c, thus can be rotated into the 10 locking position, indicated in Figure 6, or the release position as shown in Figure 4. Rivet or pin members 1g, limit the motion of grip member 1d.

The shell or body member 1, aside from being 15 provided with the elongated recess accommodating shield member 1c, also is so formed as to present a depressed platform 1e, whose perpendicular edge 1f, serves as side rest or supporting ridge for types 3, after insertion. Figure 4 indicates 20 the insertion of a type shown in dotted lines. After the types have been placed in position, shield member 1c, by means of gripping member 1d, is rotated into the locking position, see Figure 6, with this the types are securely held in position. 25

To insert or remove a type or blank, or space, shield member 1c, is rotated into the open position and the type simply lifted out by hand or if preferred by means of a suitable pair of tweezers. 30 A supporting member 2, in form of, either a portable or if more convenient a wall or table mounted, two armed bracket. Figure 3, shows a sectional side view of a wall mounted supporting member 2, whose extending side arms 2a, are suitably notched to receive body member 1. A movable lever 2b, pivoted upon one of the side arms 2a, is suitably notched to engage the wing portion of body-holder 1b, thereby securely locking the complete type setting device in position. 35

In the process of assembling the types it may 40 happen that one or the other slides off the supporting platform 1e, thus dropping into the interior of shell or body member 1, it is readily seen that due to the peculiar shape of the end 45 portions of body member 1, the removal of such type members would be extremely difficult if not impossible. Now to enable the quick removal of such a lost type a suitably dimensioned perforation 1i, is provided at preferably both ends of body member 1, see Figures 2 and 5, permitting 50 the dropping out of the type or slug, or space.

Provision is made to prevent the types from sliding off the ends of the device, by positioning 55 grip spring members 1h, similar in design as members 1d, near the ends of body member 1, as shown in Figures 1 and 2. Figure 5 indicates the locked position of members 1h.

Having thus fully described my invention, it 60 will be appreciated that the arrangement and various features may be modified in many ways within the scope of the invention.

What I claim as new and desire to secure by Letters Patent is:

1. A type setting device of the character described comprising an elongated tubular barrel

member, a suitably arranged longitudinal slot traversing the full length of said tubular barrel member, and a suitably arranged moving shield member for widening and narrowing said longitudinal slot, substantially as described. 5

2. A printing type assembling device of the character described, comprising a suitably shaped tubular barrel member, a longitudinal type receiving slot traversing the full length of said barrel member, a rotatably arranged curved shield member adapted for widening and narrowing the width of said type receiving slot, and suitable spring holding and rotating means for said curved shield member. 10

3. A printing type assembling device of the character described, comprising a suitably shaped tubular shell member, a longitudinally arranged type receiving slot traversing the full length of said shell member, a rotatably arranged curved shutter member adapted to widen and narrow 20 a portion of said receiving slot, a pair of suitably positioned slotted spring supporting and actuating means for said curved shutter member, and said supporting and actuating means partly embracing and rotating about said tubular shell member, substantially as described. 25

4. A printing type setting device of the character described, comprising a suitably shaped tubular shell member, a longitudinal slot traversing the entire length of said shell member, a 30 rotatably arranged curved shutter member adapted to widen or narrow said longitudinal slot, a pair of spaced spring supporting and rotating members fastened to said curved shutter member, and a type supporting platform suitably positioned within said shell member and presenting an integral part of the shell member, substantially as described. 35

5. A type assembling device of the character described in combination with an independently 40 mounted supporting and locking means, and said supporting and locking means comprising a suitably notched supporting bracket and a locking lever pivotally mounted thereon to securely hold said type assembling device in the operating position. 45

6. In combination a type assembling device of the character described with a portable supporting bracket, suitably arranged receiving notches provided in said supporting bracket, and an adjustable locking lever pivotally mounted upon 50 said portable supporting bracket, substantially as set forth.

7. In combination a type assembling tool of the character described with a stationary supporting means comprising a suitably shaped bracket member, a pair of extending side arms perpendicularly arranged and presenting a part 55 of said bracket, suitable tool receiving slots provided in said arms, and a pivoted locking lever suitably slotted to engage and lock said type assembling tool in its operating position, substantially as and for the purpose set forth. 60
